UNITED STATES PATENT OFFICE.

JOHN B. GLOWACKI, OF CHICAGO, ILLINOIS.

RENEWABLE INDICATOR FOR CARTRIDGE FUSES.

Application filed March 18, 1920. Serial No. 366,864.

To all whom it may concern:

Be it known that I, JOHN B. GLOWACKI, a subject of the Republic of Poland, having declared my intention to become a citizen of the United States, and a resident of the city of Chicago, in the county of Cook and State of Illinois, have invented certain new and useful Improvements in a Renewable Indicator for Cartridge Fuses; and I do hereby declare that the following is a full, clear, and exact description of the same, reference being had to the accompanying drawings, and to the numerals of reference marked thereon, which form a part of this specification.

This invention relates to a renewable indicator for encased fuses. In many cases where electric circuits are being used only intermittently it is difficult to determine whether or not the fuses in said circuit are in good condition. When a number of circuits are used it is also difficult to ascertain which of said circuits is out of order through a fuse being burned out. This is particularly true when the fibre case cartridge fuses are used, there being no means of ascertaining by an external examination whether or not the fusible metal inside the cartridge is destroyed.

It is an important object of this invention to provide a removable indicator for encased fuses whereby a burned out fuse may be easily located.

Other and further important objects of this invention will be apparent from the disclosures in the specification and the accompanying drawings.

The invention (in a preferred form) is illustrated in the drawings and hereinafter more fully described.

On the drawings:

Figure 1 is a longitudinal section of a cartridge fuse with knife contacts showing the indicating device of this invention secured in the insulating casing of said cartridge fuse.

Figure 2 is a longitudinal section taken through a cartridge fuse having clip contacts showing the indicating device of this invention secured in the outer insulating casing thereof.

Figure 3 is a top plan view of the fuse indicator of this invention.

Figure 4 is a section on line 4—4 of Figure 3.

As shown on the drawings:

The fuse indicator of this invention is mounted on a plug 1, which is formed from insulating material such as hard rubber or fibre. Said cylindrical plug 1 is provided in substantially the central portion thereof with a peripheral flange 2. The portion of the plug 1 below the peripheral flange 2 is threaded at 4 and a central aperture 3 is provided through the interior of the plug 1. The bottom of the plug 1 is countersunk at 5 to provide a tapered opening into the central aperture 3. The upper edge of the plug 1 is rounded and engaged thereover and resting on the top of the peripheral flange 2 is a domed cylinder 6, which is preferably constructed of mica or other non-inflammable transparent insulating material. A small central aperture 7 is provided in the upper portion of the domed cylinder 6. The indicating device of this invention is adapted to be secured on any form of inclosed fuse. It is shown in Figure 1 secured in the outer insulating casing 9 of a fuse 8 of the knife contact type which is fully described in my pending application for U. S. Letters Patent, Serial No. 312,343. This insulated casing 9 is apertured preferably near the central portion thereof and the threaded portion 4 of the plug 1 is engaged in said aperture. In Figure 2 the indicating device of this invention is shown secured in the outer casing 11 of a clip contact type of fuse which is fully described in my pending application for U. S. Letters Patent, Serial No. 312,340. An aperture 12 is provided preferably near the central portion of the outer casing 11 of said fuse 10 and the lower threaded portion 4 of the plug 1 is engaged therein. An aperture 14 is provided in the inner insulating casing of the fuse 10 directly below the aperture 12 in the outer casing 11 in order that the indicating device of this invention may be in communication with the chamber in which the fusible element 15 is contained.

The operation is as follows:

The indicating device of this invention is secured in the outer casing of the fuse on which it is to be used by threading the threaded portion 4 of the plug 1 in an aper-

ture in said outer casing. As heretofore indicated, provision is made for the indicating device of this invention to be always in communication with the chamber in which the fusible element 15 is contained. When said fusible element 15 is burned out due to a short circuit on the line or excessive current flowing therethrough the force of the burning out explosion will affect the indicating device of this invention in various ways. In case of a severe short circuit the force of the blowing out of the fuse will either blow the domed cylinder from the plug 1 or crush the cylinder so that the fact of the fuse being burned out will be easily discernible from the exterior of the casing. In case of a slower burning out of the fuse where a less violent explosion takes place the transparent domed cylinder 6 will be discolored in such a manner that an external inspection clearly indicates that the fuse therein was damaged. On account of the aperture 7 in the top of the domed cylinder 6, smoke from the burned fuse will issue therefrom for some time after the fuse 15 has burned out. Thus if an inspector comes into the room within any reasonable time after the burning out of the fuse 17, his attention will be called to the fact that the fuse has burned out by the smoke which is rising from the aperture 7 in the cylinder 6. It is of course to be understood that the indicating device of this invention may be applied to any type of enclosed fuse whether removable or rigid and that it provides a convenient means for determining whether the fusible element inside the enclosing means is burned out thereby greatly facilitating the inspection of the fused electric circuit.

40 The inspector or repairman can carry several extra transparent indicating cylinders in order to replace those that are broken, lost, or discolored at the same time the fuse is renewed.

45 I am aware that numerous details of construction may be varied through a wide range without departing from the principles of this invention, and I therefore do not purpose limiting the patent granted otherwise than necessitated by the prior art.

I claim as my invention:

1. A fuse indicator comprising an internally apertured plug, an external flange

thereon, and a transparent indicating device engaged over one end of the plug and 55 abutting the flange.

2. A fuse indicator comprising an internally apertured plug, an external flange thereon, and a transparent indicating cylinder of non-inflammable insulating material 60 engaged over one end of the plug and abutting the flange.

3. A fuse, a casing enclosing said fuse, said casing having an aperture therein, a tube lining said aperture, and a transparent 65 closure for said tube.

4. A fuse, a casing enclosing said fuse, said casing having an aperture therein, a closure for said aperture, said closure having an open perforation smaller than the 70 aperture in the casing.

5. A fuse, a casing therefor, said casing having an aperture therein, and a dome-shaped member of transparent material secured over said aperture. 75

6. A fuse, a casing therefor, a tube through the wall of said casing and a dome-shaped closure for the end of said tube, the height of the dome being greater than the thickness 80 of the wall of the casing.

7. A fuse, a casing therefor, a tube through the wall of said casing and a dome-shaped closure frictionally mounted on said tube.

8. A fuse, a cylindrical casing therefor having a hole in the side thereof, a tube 85 screwed in said hole and countersunk on its inner end.

9. A fuse, a cylindrical casing therefor, having a hole in the side thereof, a tube screwed in said hole and countersunk on its 90 inner end, and a dome-shaped cover frictionally mounted on the outer end of said tube.

10. A fuse, a cylindrical casing therefor having a hole in the side thereof, a tube screwed in said hole and countersunk on its 95 inner end, and a dome-shaped cover on the outer end of said tube, and said dome having an open hole opposite the mouth of said tube.

In testimony whereof I have hereunto 100 subscribed my name in the presence of two subscribing witnesses.

JOHN B. GLOWACKI.
